[57] CLAIM

The ornamental design for a combined shoe bottom and periphery, as shown and described.

DESCRIPTION

FIG. 1 is a perspective view of the front, right and bottom of a shoe bottom and periphery showing my new design.

FIG. 2 is a right side elevational view thereof;

FIG. 3 is a left side elevational view thereof;

FIG. 4 is a bottom plan view thereof;

FIG. 5 is a front elevational view thereof; and

FIG. 6 is a rear elevational view thereof;

The broken line showing the shoe upper in the figures is for illustrative purposes only and forms no part of the claimed design.
